DRESS SHIELD

Sadie Bendersky, South Orange, N. J.

Application October 17, 1936, Serial No. 106,154

3 Claims. (Cl. 2—53)

This is a continuation in part of my original application for patent on Dress shield and method of making the same, filed May 7, 1936, Serial No. 78,417.

5 My invention relates to shields for the protection of the under-arm portions of garments, such as dresses, blouses, and the like, from discoloration and deterioration due to contact with the perspiration of the wearer. More particularly, 10 my invention relates to novel and practical means for detachably securing such shields to the under-arm portions of dresses in a manner to render the presence of the shield unnoticeable from the outside of the dress while at the same time ensuring a maximum of comfort to the wearer.

15 Dress shields have presented a variety of problems which have made their use difficult and, though necessary, nevertheless discommodious. Thus, the very utilization of dress shields requires 20 that they be frequently removed for washing and replacement. This has led to the common practice of locating, sewing, and ripping out, and relocating and resewing shields into place; and to various attempts to provide substitute means 25 for detachably securing dress shields into place. None of these means as yet produced, has proven ultimately satisfactory. Thus, attempts at solving 30 these problems have resulted in "bunching" the dress shield or the detachable fastening means thereof in the arm pit, so as to render the wearer decidedly uncomfortable. Or they have resulted 35 in the use of metallic fastening means coming directly in contact with the flimsy dress material; thereby occasioning rips and unsightly holes in the dress, and considerable discomfort to the wearer whenever her body comes in contact with the metal. Also, considerable difficulty has been 40 experienced in properly locating the dress shield in place each time it is to be reattached to the dress.

45 Moreover, a desideratum of dress shields is that their presence be inconspicuous, and unnoticeable on the outside of the dress. Yet the dress shields sewed directly on the dress outline thereon their presence, by lending their stiffness to the pliant dress material to which they are so closely united. Furthermore, detachably secured dress shields having stiff fastening means directly on the dress, pull on the dress whenever the arm is moved, 50 thereby betraying their presence; for the stiff fastening means cannot respond to an external pull in the same manner as the flexible dress material. Also, the presence of any stiff material whatsoever, conjoined directly to the dress at the 55 under-arm portion thereof, renders the dress stiff at the very portion of the dress which requires the greatest flexibility.

60 It is an object of my invention, therefore, to provide a dress shield with means thereon for flexibly securing the same to a dress in a man-

ner to render the presence of the shield unnoticeable from the outside, regardless of the position of the wearer thereof; and in a manner to permit a maximum of flexibility to the under-arm portion of the dress itself.

5 Another object of my invention is to provide means for detachably securing a dress shield to a dress in a manner to render the shield easily and readily attachable, easily removable, and as easily reassemblable; said means to occupy a 10 minimum of space, and to render a maximum of comfort.

A further object of my invention is to provide 15 means for easily locating and relocating dress shields into place.

A further object of my invention is to provide 20 a combination of temporary shield, fastening means, and dress shield, whereby a temporary shield, for use in retail dress shops, may be detachably secured to a dress, and then discarded 25 for a more permanent dress shield, securable to the dress by the same fastening means; both shields bearing similar characteristics of ease and simplicity in assembly, and comfort to the wearer, as well as inconspicuousness to the observer.

25 With the above and other objects in view, my invention consists of the combination of a dress, a dress shield, and a flexible nexus; said flexible nexus being secured at one portion thereof to said dress, and another portion being in interlocked 30 condition with said dress shield; and means spaced from the portion of said dress secured to said nexus, for releasably maintaining said interlocked condition.

35 My invention also consists of a dress shield comprising a fabric having interlocking means in proximity to the periphery thereof; an absorbent-paper dress shield of substantially the same size and configuration as said first-mentioned dress shield; and a flexible nexus having a plurality of 40 coacting detachable-engaging means contiguous to both ends thereof and adapted alternately to interlock with said interlocking means on said fabric, and with said absorbent-paper shield; the transverse median portion of said nexus being 45 adapted to be sewed to a dress.

46 My invention also consists of various combinations of the constituent characteristics of my invention, as will appear more fully hereinafter.

50 For the purpose of illustrating my invention, I have shown in the accompanying drawing forms thereof which are at present preferred by me, since the same have been found in practice to give satisfactory and reliable results, although it is to be understood that the various instrumentalities 55 of which my invention consists can be variously arranged and organized and that my invention is not limited to the precise arrangements and organizations of the instrumentalities as herein shown and described.

Referring now to the drawing, in which like reference characters indicate like parts:

Figure 1 represents a fragmentary perspective view of a dress shield assembly embodying my invention, whereby the flexible nexus and fastening means embodied in my invention are used for successively securing to a dress, a temporary absorbent-paper shield, and a permanent shield.

Figure 2 represents a front elevational view of a dress shield embodying my invention.

Figure 3 represents a front elevational view of a dress shield of modified construction embodying my invention.

Figure 4 represents a fragmentary view, in perspective, of the under-arm portion of a dress with the dress shield of another modified construction, embodying my invention, assembled therewith.

In accordance with my invention, I provide a dress shield 10 adapted to be inserted within the arm scye 11 of a dress 12; said dress comprising a waist 13 and a sleeve 14; and said dress shield comprising a waist portion 15 adapted to be inserted between the waist 13 of the dress 12 and the body of the wearer, and a sleeve portion 16 adapted to be inserted between the sleeve 14 and the arm of the wearer. For the purposes of illustration, I have shown in the drawing a seam 17, joining the sleeve 14 with the waist 13, at the arm scye 11; and also a side and sleeve seam 18 extending downwardly from the arm scye 11 towards the waist, and also towards the cuff.

Along the median axes of the waist portion 15 and the sleeve portion 16, and also in proximity to the fold 19 forming the juncture of said waist and sleeve portions 15 and 16, I provide eyelets 21, in proximity to the periphery 22 of the shield 10 and extending through said shield.

Flexible nexus, such as flexible tabs 23, or the like, are provided, each having secured to one end thereof a female snap fastening member 24, and to the other end thereof a male snap fastening member 25; said male snap fastening member 25 having a spear-post 26 extending therefrom. This spear-post 26 may be of the conventional ball-headed type, but must be of a height sufficient to pass the ball or spearhead thereof through the eyelet 21. The transverse median portion 27 of the flexible nexus or tab 23 is adapted to be sewed to a dress 12.

A temporary shield 28, preferably of absorbent paper, is also provided, having a size and configuration similar to that of the more permanent shield 10.

In practice, the flexible nexus or tabs 23 are detachably secured to the dress shield 10 by means of the male spear-posts 26 thereon, passing through the dress shield eyelets 21, and being snapped into interlocking engagement with the female socket members 24 on the opposite ends of the tabs 23. This positions the transverse median portion 27 of the tabs 23 a short distance beyond the periphery 22 of the dress shield 10.

The dress shield is then inserted within the arm scye 11 of the dress 12, with the tabs 23 in juxtaposition to the seams 17 and 18 of the arm scye, waist and sleeve portions, respectively; and the transverse median portions 27 of the flexible nexus 23 sewed thereto. The dress shield 10 is then detached from the nexus 23 by disengaging the male snap fasteners 25 from the female snap fasteners 24 and passing the spear-posts 26 out of the eyelets 21; and the dress shield is removed from the dress.

A temporary shield 28 is then inserted within the arm scye 11 in the same relative position as

that formerly held by the dress shield 10. This places the periphery 29 of the shield 28 in proximity to the transverse median portion of each of the nexus 23, with the female socket members 24 on one side of the shield 28 and the male spear-post members 26, facing them, through the other. The male spear-posts 26 are then urged through the absorbent paper temporary shield 28 and snapped into engagement with the female socket members 24. This secures the temporary shield 10 in place.

The temporary shield may be used on the dress for the purpose of protecting it from becoming shopworn or deteriorated due to contact with the perspiration of prospective purchasers who "try on" the dress; and tends to keep it fresh until ultimately purchased. Moreover, it may be used as a temporary substitute for the more permanent dress shield while the latter is being washed and dried; or a series of temporary shields may be preferred by a customer to one permanent shield.

When it is desired to discard the temporary shield 28 and substitute in place thereof a permanent dress shield 10, it is merely necessary to disengage the snap fastener members 24 and 25 and withdraw the spear-post 26, thereby releasing the temporary shield 28; and substitute in place thereof the permanent shield 10, which is secured in place by simply passing the spear-posts 26 of the male members 25 through the dress shield eyelets 21, and snapping them into engagement with the female socket members 24, as hereinbefore described.

Should it be desired to wear the dress without any shields whatsoever, it is merely necessary to bring the male and female fasteners 24 and 25 into "snapped" engagement. The metal parts are thereby withdrawn from possible contact with the wearer, for the flexible tabs 23, being positioned at the base of each member of the snap fastener, serve to cover that member from contact with the wearer.

In Figure 2 is illustrated a modified form of dress shield embodying my invention, wherein the fastening means are borne by the shield, and not by the flexible nexus; and the interlocking eyelet is formed instead, on the nexus.

Thus, in this modification of my invention, I provide a dress shield 10 having a juncture fold 19. Flexible yokes 30 having a cantilever side 31 and a free side 32, are secured to the shield 10 by means of said cantilever side 31, preferably along the marginal region 33 of the shield 10, and in proximity to its median axis and to its juncture fold 19. To the inner faces 34 and 35 of the yoke sides 31 and 32, I secure a male snap fastening member 36, and a female snap fastening member 37, respectively. The male snap fastening member 36 preferably has a spear-post 38 of sufficient height to pass the head thereof through the fabric eyelet 39 yet to be described.

A flexible nexus 40, which may be a flexible tab, is provided, having formed near one end 41 thereof the eyelet 39. The other end 42 thereof, is adapted to be sewed to a dress.

In practice, the end 41 of the flexible nexus 40 is inserted within the flexible yoke 30 with the eyelet 39 in interlocking engagement with the spear-post 38 of the male fastening member 36. The female fastening member 37 carried by the free end 32 of the flexible yoke 30, is then brought into "snapped" engagement with the male fastening member 36. The dress shield is then inserted in place within the arm scye of the

dress and the ends 42 of the flexible nexus 40 are sewed to the dress.

When it is desired to remove the dress shield, as for washing or replacement, it is but necessary to release the snap fastening members 36 and 37 and disengage the interlocked eyelet 39 and spear-post 38. The shield may then be removed and there is left on the dress but the flexible nexus 40, which easily conforms to the folds of the dress and is unnoticeable. When it is desired to return the shield to the dress, there is no fuss or bother about locating the proper place in the arm hole for placing the shield. The shield 10 is merely reinserted therein with its yokes 30 placed in juxtaposition to the eyelet ends 41 of the flexible nexus 40, and the nexus and yokes brought into releasably secured interlocking engagement, as hereinbefore described. The shield is now reassembled with the dress, 20 ready for wear.

It will be noted that here, too, the metal parts are covered from contact with the body of the wearer, by the fabric covering formed by the supporting flexible fabric, in the case of this 25 modification, the yoke.

In Figure 3 is illustrated another modified form of dress shield embodying my invention, wherein the yoke itself is brought into interlocking engagement with the flexible nexus.

30 Thus, in this modification of my invention, I provide a dress shield 10 having a juncture fold 19, and a marginal region 33. Flexible yokes 43, having a cantilever side 44 and a free side 45, are secured by means of said cantilever side to 35 the shield 10, preferably along the marginal region 33 thereof and in proximity to its median axis and to its juncture fold 19. Coactable releasable securing means, such as the non-metallic button 46 and the buttonhole 47 are provided 40 on the opposed sides of the flexible yoke 43. A flexible nexus 48 comprising a flexible fabric annulus or ring is provided, of sufficient size to enable the end 45 of the yoke 43 to pass therethrough.

45 In practice, the end 45 of the flexible yoke 43 is passed through the flexible nexus ring 48, and the button 46 is passed through the buttonhole 47, thereby releasably securing the flexible nexus 48 in interlocked condition with the flexible yoke 43. The shield is then inserted in position in 50 the arm hole of a dress and the end 49 of the flexible nexus 48, opposed to the portion thereof interlocked with the yoke 43, is then sewed to the dress.

55 When it is desired to remove the shield, as for washing or replacement, it is merely necessary to unbutton the releasable securing means and pass the yoke 43 out of engagement with the ring 48, and the shield is free. When it is desired to reassemble the shield with the dress, the shield is inserted in the arm hole of the dress, with the yokes 43 in juxtaposition to the flexible nexus rings 48 and the yokes and rings are brought into releasably secured interlocking engagement, as hereinbefore described. If it is desired to wear 60 the dress without the shield, it can very readily be done, for the nexus rings are small and flexible, and contact the dress at but one point, thereby ensuring flexibility at the ever-torsioned arm 65 scye of the dress.

70 In Figure 4 is illustrated a further modified embodiment of my invention. In this embodiment, I provide a dress shield 10 having a junc-

ture fold 19 and a marginal region 33. In proximity to the marginal region 33, and also to the median axis of the shield as well as to the juncture fold 19 thereof, I provide eyelets 50 adapted to interlock with a narrow, flexible nexus 51 passing therethrough.

5 A collar 52 is slidably mounted on the narrow, flexible nexus 51, and is prevented from sliding off of one end 53 of the nexus, by a knob or knot 54 found on said end 53. The other end 55 of the narrow, flexible nexus 51 is adapted to be sewed to a dress 12.

In practice, I pass the collar 52 through the eyelet 50, which must be flexed to receive it, until it has passed to the opposite side of the dress 15 shield, and has threaded with it, the flexible nexus. The nexus is now interlocked with the eyelet. Moreover, this interlocked condition is releasably maintained by the collar 52 abutting against the opposed face of the eyelet 50. To 20 release the dress shield from the nexus, it is but necessary to flex the eyelet 50 and urge therethrough the collar 52 and flexible nexus 51. The dress shield is then free to be removed or replaced.

25 I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I 30 hereby claim as new and desire to secure by Letters Patent is:

1. A dress shield comprising a fabric and a detachable flexible tab; an eyelet in proximity to the periphery of said fabric; and a plurality 35 of co-acting detachable-engaging means secured to said tab and in interlocking engagement with said eyelet; a portion of said tab, spaced from said detachable-engaging means, being adapted to be sewed to a dress.

2. In combination, an absorbent fabric dress shield; a dress; a flexible tab secured at one portion thereof to said dress; detachable-engaging means secured to said tab and spaced from said portion; said detachable-engaging means being 50 detachably secured to said absorbent fabric shield.

3. The method of assembling an absorbent fabric dress shield with a dress, comprising the provision of a dress; an absorbent fabric dress shield; 55 and a dress shield comprising a fabric and a detachable flexible nexus; an eyelet in proximity to the periphery of said fabric; and a plurality of co-acting detachable-engaging means secured to said nexus and in interlocking engagement 60 with said eyelet; positioning said last-mentioned dress shield in said dress; sewing a portion of said nexus, spaced from said detachable-engaging means, to said dress; detaching said detachable-engaging means and withdrawing said nexus 65 from interlocking engagement with said eyelet; withdrawing said dress shield fabric; inserting said absorbent fabric shield in said dress in juxtaposition to said flexible nexus; and detachably securing said detachable-engaging means 70 to said absorbent fabric shield.

SADIE BENDERSKY.
